VOLTAGE AND CURRENT LIMITER

James Ernest Smith, Brooklyn, N. Y., James N. Whitaker, Weehawken, N. J., and Gilbert E. Clark, Brooklyn, N. Y., assignors to Radio Corporation of America, a corporation of Delaware

Original application April 27, 1939, Serial No. 270,332. Divided and this application May 4, 1940, Serial No. 333,272

6 Claims. (Cl. 178—44)

This invention relates to a current or voltage limiting device and is a division of our application Serial No. 270,332, filed April 27, 1939, now Patent No. 2,257,282, issued Sept. 30, 1941.

An object of the invention is to provide an electron tube limiter using negative cut-off on both half waves of the signal voltage, both half waves being produced by the same input coil.

Another object is to provide an improved limiter capable of maintaining a constant output with a widely varying input.

Other objects will appear in the following description, reference being had to the drawing in which:

Fig. 1 is a diagrammatic illustration of the 15 voltage limiter.

Figs. 2 to 7, inclusive, are graphs illustrating the operating characteristics of the limiter.

Referring to Fig. 1, the alternating current to be limited enters the input 1 of transformer 2, across which is connected load resistance 3. The grid circuit of amplifier 4 is adjustably connected to resistance 3 and the output is connected to the grid circuit of push-pull amplifier 5 through transformer 6. The grid leads of the push-pull tubes may have resistances 7, 8 to aid in the limiting action, but these may be omitted and the entire limiting action performed by the main limiter later described.

The output of the push-pull amplifier is connected to the rectifying device by transformer 10. The rectifier consists of four rectifiers, 11, 12, 13 and 14, which are so arranged that the rectified current for each half wave passes through two rectifiers in series and connected so that both half waves are produced by the same coil, in this case secondary 15. The cathodes of rectifiers 11, 13 are connected by adjustable tap 16 to potentiometer resistance 17, one end of this resistance being connected to the positive terminal 18 of a source of supply, the other terminal 19 of this source being grounded. It is preferable to use this resistance 17, but it can be omitted if no threshold limiting by the rectifiers is desired.

The anode of rectifier 11 is connected to the cathode of rectifier 14 and the anode of rectifier 13 is connected to the cathode of rectifier 12. The anodes of rectifiers 12 and 14 are connected to the grids of tubes 20 and 21 and resistance 22 is connected across these grids, the center of the resistance being grounded. Of course, the grids may be connected to intermediate points of this resistance instead of to the plate terminals thereof. The cathodes of tubes 20 and 21 are connected by adjustable tap 23 to potentiometer re-

sistance 24, one end of which is connected to the positive terminal 18 and the other one of which is connected to negative terminal 19 through ground. This resistance is a source of negative bias for tubes 20 and 21. The anodes of tubes 20 and 21 are connected in push-pull fashion and are fed from the source 18 in the usual way, as is indicated in the drawing.

The operation will now be described. As the signal or other alternating current passes into the limiter through input conductors 1, 2, it is amplified by the single stage 4 and passes into the input of the push-pull stage 5. The output of the stage 4 is introduced into the rectifier input. Assuming that the slider 16 is adjusted to the ground terminal of resistance 17 and that terminal 25 of resistance 26 is for the moment positive, signal current will pass from the anode of tube 11 to its cathode, through adjustable contact 16 to ground and from ground to the lower part of resistance 22, to the anode of tube 12, thence to its cathode and to the terminal 27 of the resistance 26.

When terminal 27 is positive, signal current will pass from the anode to the cathode of tube 13, thence through contact 16 to ground, through the upper part of resistance 22, from the anode to the cathode of tube 14 and thence to terminal 25.

In Fig. 2, 28 represents the drop in the lower half of resistance 22 for one half wave and 29 the drop in the upper half for the other half wave. If an oscillograph, for example, were placed across the whole of resistance 22, it would produce an alternating voltage of the shape of the graph 28, 29.

By sliding the contact 16 towards the positive side of resistance 17, a counter E. M. F. is introduced in the rectifier circuit and the part of the wave extending from the zero axis to the lines c, d will be eliminated, as it is below the counter E. M. F. threshold. The portion beyond these lines will be all that is passed. The form of the wave with this adjustment of slider 16 will be as indicated at 30, 31 in Fig. 3. The amount of threshold action can be made anything desired by adjusting the contact 16.

The half wave potential applied across the grid and cathode of tube 21 is like either 28 or 30, depending upon the adjustment of slider 16 for regulating counter E. M. F. Similarly, the half wave across the grid of tube 20 is like either 29 or 31. The shape of the waves appearing in the primary of the output of the push-pull stage 20,

21 depends on the adjustment of contact 23, which places a negative bias on the grids.

Assuming for purpose of explanation that an appropriate negative bias has been placed on the grids of tubes 20 and 21 from resistance 24, the steady electron flow in tube 21, that is, when no signal voltage is applied to the grid, may be of the value indicated by line B, B of Fig. 4 and that of tube 20 by line B', B', Fig. 5, one being reversed in reference to the other, because of the push-pull connection of the plate coils. With slider 16 on the ground end of resistance 17, the current flow through the plate circuit of tube 21 in one complete cycle of the signal will be indicated by graph 32 of Fig. 4. The first half of the cycle is the reduced electron flow produced by the half wave 28 applied as a negative voltage to the grid of that tube and the last half of the cycle of this tube is the higher and steady electron flow with no signal voltage applied to the grid.

During the same complete cycle the current flow in the plate circuit of tube 20 is indicated by graph 33 of Fig. 5. In both of the graphs 32 and 33 the signal drives the grids to and below negative cut-off, the parts of the wave cut-off being indicated by the dotted lines. It will be apparent that the current, or voltage, in the output circuit 36 will be a combination of curves 32 and 33 such as is indicated by graph 34 of Fig. 6 or graph 35 of Fig. 7, depending upon the adjustment of slider 16 on resistance 17.

The limiter of our invention utilizes the entire input coil or transformer secondary for each half of the wave and the input impedance of the rectifiers is therefore identical, which is not true of prior art rectifiers. This is an important feature.

Various modifications may be made without departing from the spirit of our invention.

Having described our invention, what we claim is:

1. In a limiting device, input lines, a pair of resistances, a pair of rectifiers connected together through one resistance and across said lines to conduct current there through in one direction, a second pair of rectifiers connected together through the other resistance and across said lines to conduct current therethrough in the opposite direction, a connecting link between the ends of the resistances where the rectified current enters therein, a pair of electron tubes having their cathodes connected to said link and their control electrodes connected to points adjacent the other ends of said resistances and means for combining the output voltages of said tubes.

2. In a limiter for a signaling system, a signal source, two pairs of rectifiers, a pair of resistances, means for connecting each pair of rectifiers in series in a conducting circuit across said signal source through one of said resistances for full wave rectification, a pair of electron tubes having cathodes connected to said resistances and having control electrodes connected to points in said resistances that are negative in respect to the connection of said cathodes with said resistances and means for combining the output voltages of said tubes.

3. In a limiter for a signaling system, a signal source, two pairs of rectifiers, a pair of resist-

ances, a source of electromotive force, each pair of rectifiers being connected in series in a conducting circuit across said signal source through one of said resistances and through said source of electromotive force in opposition to the voltage therein for full wave rectification, a source of negative grid bias, a pair of electron tubes having cathodes connected to said resistances through said source of negative grid bias and having control electrodes connected to points in said resistances that are negative in respect to the connection of the said cathodes with said resistances and means for combining the output voltages of said tubes in phase opposition.

4. In a limiter for a signaling system, a signal source, two pairs of rectifiers, a pair of resistances, means for connecting each pair of rectifiers together through one of said resistances in a series conducting circuit across said signal source for full wave rectification, a pair of electron tubes having cathodes joined together and connected to positive equipotential points of said resistances and having their control electrodes connected to negative equipotential points of said resistances, means for biasing said control electrodes negative in respect to said cathode, the negative potential thus applied to the grids being sufficient to block the anode currents at a predetermined value of the signal potential in the resistances and means for combining the output voltages of said tubes in phase opposition.

5. In a limiting device, input terminals, a pair of rectifiers connected in a series circuit across said terminals to conduct current in one direction, a second pair of rectifiers connected in a series circuit across said terminals to conduct current in the opposite direction, a pair of vacuum tube amplifiers, means including a resistance in the first-mentioned series circuit for impressing a negative potential on the input electrodes of one amplifier tube from the first-mentioned current, means including a resistance in the second-mentioned series circuit for impressing a negative potential on the input electrodes of the other amplifier tube from the second-mentioned current and means for combining the output voltages of said amplifiers.

6. In a limiting device, input terminals, a pair of rectifiers connected in a series circuit across said terminals to conduct current in one direction, a second pair of rectifiers connected in a series circuit across said terminals to conduct current in the opposite direction, means for connecting the junction point of the rectifiers of one pair to the junction point of the rectifiers of the other pair, a pair of vacuum tube amplifiers, means including a resistance in the first-mentioned series circuit for impressing a negative potential on the input electrodes of one amplifier tube from the first-mentioned current, means including a resistance in the second-mentioned series circuit for impressing a negative potential on the input electrodes of the other amplifier tube from the second-mentioned current and means for combining the output voltages of said tubes in phase opposition.
